NUT MARKING DEVICE

John E. Trunk, Newberg, Oreg.

Application June 18, 1934, Serial No. 731,123

15 Claims. (Cl. 101—37)

The present invention has to do with a device for marking or branding nuts and like articles. The problem of such branding is made difficult by the many variations in size of the objects to be branded, their uneven surfaces, and the fact that they are not regular in shape. Since they are rarely spherical they must be placed and held in some particular position while being marked.

The most obvious way of branding such objects is to make an ink impression on their tops as they pass on a belt under a printing apparatus. When this is done the variations in size make necessary a sorting of the objects to be branded or else some way of compensating for the comparatively wide variance. This necessity either increases the cost or reduces the efficiency of the device.

The objects of this invention are to avoid those and similar difficulties and are as follows:

A new and improved machine for marking nuts and like articles not of uniform size and shape.

A device for placing a stamp uniformly upon uneven rounded small articles such as nuts.

A marking device allowing properly for differences in size and shape of articles to be marked.

An efficient and economical branding machine.

A marking device capable of operating at high speed.

A marking device capable of handling rapidly large quantities of articles to be marked.

A novel structure for carrying belts for small articles.

A novel structure for loading small articles onto a conveyor.

A novel device for seating small articles in a conveyor.

A novel inking device for marking rollers.

A novel structure for printing rollers.

A novel adjustable carriage and adjusting means for printing and inking rollers.

A novel structure for holding articles to be printed.

A novel way and device for presenting small articles to a printing roller or device for marking.

Many other objects will appear from the description of the machine hereinafter given.

In the drawings of the illustrated embodiment of the invention:

Figure 1 is an elevation of the right hand side of such machine;

Figure 2 is an elevation of the left hand side of the machine shown in Figure 1;

Figure 3 is a plan view of the same machine;

Figure 4 is a vertical sectional view on line 55 4—4 of Figure 3;

Figure 5 is a sectional view of one of the carrier belt bars through one of the cups, on line 5—5 of Figure 3;

Figure 6 is an end view of the printing roller with part of one bar thereon cut away to a sectional view through one of the rubber dies therein, on line 6—6 of Figure 8;

Figure 7 is an end view of the printing and inking frame with the end frame removed but indicated by dotted lines;

Figure 8 is a plan view of the printing and inking frame; and

Figure 9 is a view of the carrier belt showing details thereof.

Like reference characters are used to designate similar parts in the drawings and in the description of the invention hereinafter given.

The main supporting structure for the device is a frame 20, made of metal beams or other suitable materials bolted, riveted or welded together. 20 There are four upright pieces, 21, joined by horizontal beams 22 at the top, 23 in the middle, and 24 at the bottom, on the right side, 25 at the top, 26 in the middle and 27 at the bottom on the left side, and cross pieces 28, 29 and 30, and 31, 25 32, and 33 at the ends. The entire frame may be mounted on casters or wheels 34, so that it may be moved about.

At one end of the machine, there is a hopper 35, and at the other a sacking chute 36 having two outlets 37 and 38, and a movable vane 39, operated by handle 40 to deflect branded nuts or other articles into one or the other outlet.

Mounted above the chute 36, or at some other place, may be a switch box 41 for starting and stopping the device.

The bottom 42 of the hopper does not extend entirely to the lowest part thereof, but terminates above that point. To this abbreviated bottom there is fastened, as by screws 43 or in any other 40 way, a sheet of elastically flexible material 44, such as sheet metal.

The flexible sheet 44 extends entirely across the hopper and forms a continuation of the bottom of the hopper. At the other edge of the 45 sheet 44, there is attached a heavier piece of material 45, also extending entirely across the hopper and forming a further extension of the abbreviated bottom. The piece 45 is heavy enough to carry rigid tail pieces 46 which are fastened 50 to it in any desirable way, as by bolts 47.

The carrying device consists of a continuous belt 48 comprising chains 49 at each side to which are fastened carrier bars in the usual way. In the forms shown, the pins of the sprocket 55

chains 49 hold links 51 which are bolted to the ends of the carrier bars.

In each carrier bar there are a plurality of recesses 52 to receive articles 53 to be marked.

5 The recesses 52 are cup shaped, the particular conformation depending on the nature of the articles to be marked. In the present form of the invention the recesses are oval in shape because that shape best fits the nuts 53.

10 The recesses 52 are open at the bottom, at 54, as indicated. Into this opening a small portion of the article 53 will project. The amount projecting will vary slightly with objects of different sizes, but the variation will be slight. The openings 54 may be shaped according to the shape of the article or instead, they may be shaped according to the shape of the mark that is to be placed on the article. In the present instance, the oval shape of the opening fills both requirements.

Near to and below the piece 45 and the tail pieces 46, the chains 49, supporting the carrier bars 50, are carried on idler sprockets 55, mounted on shaft 56 which is journaled in bearings 57 and 58 mounted adjustably on the horizontal frame pieces 23 and 26. Bolts 59 and 60 on each side pass through slots in the bearing supports or in the frame members and may be loosened and the bearings moved one way or the other 20 to tighten or loosen the belt 48. The same movement also adjusts the distance between the belt 48 and the hopper 35. Grease cups 61, or any other available means, may be provided to keep the bearings oiled.

35 Upward and towards the middle of the machine from the idler sprockets 55 are sprockets 62 and 63, engaging the chains 49, and keyed to shaft 64, which is journaled in bearings 65, fastened, as by bolts 66, to the top frame members 22 and 25, on each side. The shaft 64 extends beyond the bearings on each side of the machine to receive other sprocket wheels and cams.

Near the end of the machine away from idler 45 sprockets 54 and 55 and near the top of the machine, are drive sprockets 67 and 68 over which chains 49 pass carrying the carrier bars 50. These sprockets are keyed to shaft 69 which is journaled in bearings 70 fastened to frame members 22 and 25 in the usual way. Shaft 69 is extended at one end to receive driven sprocket 71 which is keyed to the shaft.

Below the drive sprockets 67 and 68, and somewhat nearer the middle of the length of the machine, are idler sprockets 72, mounted on shaft 72a which is journaled in bearings 73 mounted on the frame members 23 and 26. The carrier belt thus runs on four pairs of sprockets, one drive sprocket, one driven sprocket and two idler sprockets. The path of travel is upward from the first idler sprocket and from the hopper, over the driven sprocket, over the drive sprocket, down to the second idler sprocket and thence loosely back to the starting point.

65 Near the hopper 35 and immediately above a part of the upward slope of the carrier belt 48, is a revolving brush of uniform cylindrical shape 74, which in use is rotated so that the part nearest the belt is traveling in a direction opposite to that of the travel of the belt. This brush keeps back any surplus nuts that may appear upon the belt and helps to seat the nuts in the depressions in the carrier bars. The brush is mounted on shaft 75, which is journaled in bearings 76 and 77. The bearings 76

and 77 are mounted adjustably upon angular frame pieces 78 afforded for the purpose, attached to the two adjacent uprights 21, and to the sheet metal triangular enclosing members 79 which serve to enclose the side ascending portion of the carrier belt. The bearings are adjustable to raise or lower the brush, in the usual manner, such as by slots in the frame or in the base of the bearing, not shown in the drawings. The shaft 75 is extended at the left hand side of the machine, to carry the driven sprocket 80, which is keyed to the shaft. A chain 81, passing around sprocket 82, which is keyed to the shaft 64 of the sprockets 62 and 63, turned by force transmitted through the carrier chains 49, causes sprocket 82 and the brush 74 to revolve when the carrier chain is in motion.

Below the ascending portion of the carrier belt 48 and in position to support it if it should tend to sag are supporting slide members 83 supported by the leg members 84 and 85 through the medium of angle irons and bolts in the usual way.

Above the horizontal portion of the carrier belt 48 between the driven sprockets 62 and 63 and drive sprocket 71 is a further set of brushes to adjust the nuts in the recesses in the carrier belt and cause them to be seated properly therein. The brushes 86 and 87 are flat and are mounted upon supporting frame members 88 and 89 with the ends of the bristles either upon or adjacent to the carrier bars 50. At the end away from the hopper 35, frame members 88 and 89 are fastened, as by bolting or riveting, to a cross frame member 90. These frame members 88, 89 and 90 are commonly L shaped in cross section, but the shape is a matter of choice.

At each end of the cross frame 90 means is provided either by the use of angle irons or by bending one side of the L for a fastening by a bolt or pin parallel to the long axis of the member. By means of such bolts or pins 91 and 92, links 93 and 94 are pivotally secured to each end of the cross frame member 90. The links 93 and 94 are adjustably secured by bolts 95 passing through slotted holes 96 to links 97 and 98, which in turn are pivotally connected to top frame members 22 and 25.

The other ends of the frame members 88 and 89 are bent inwardly at an angle at a point just short of the brushes from the hopper end of the machine, and the inwardly turned ends are fastened as by bolts 99 and 100, to the bearing 101. A cross piece 102 is fastened to the frame members 88 and 89 between the bend and the brushes. To the middle of the cross piece is attached a second bearing 103 in line with the first 101.

Through bearings 101 and 103 but not extending beyond bearing 103 towards the brushes is a shaft 104 which is locked rotatably in place in the bearings by the collars 105 and 106 placed on the shaft between the bearings, and secured by set screws 107 and 108.

On the outer end of the shaft 104 is a connecting collar 109 having an opening to receive the outer end of the shaft and a set screw to hold it securely in place, and having an aperture at right angles to the axis of the shaft 104 to receive a pin 110. The pin 110 carrying the collar 109 and a spring 111 to take up slack passes between the ends of a substantially U-shaped cam rider 112 being held in place by lock nuts 113 or in any other suitable way. The cam rider 112 is not fully U-shaped because what would be

the bottom of the U is bridged over to form a circular opening which receives rotatably the central part of a grooved wheel 114.

The grooved wheel 114 is mounted rotatably upon an angularly disposed extension 115 of shaft 116, being held in place by a collar 117 provided with a set screw 118.

Shaft 116 is journalled in bearings 119 and 120 which are mounted upon a cross member 121 fastened to main frame members 22 and 25. Bolting appears to be the most satisfactory way of fastening these various parts together.

An end of the shaft 116 extends beyond frame member 25 on the left hand side of the machine and to it is keyed a sprocket 122 which cooperates with a chain 123 driven by sprocket 124 keyed to shaft 125 to rotate shaft 116 and cause the brushes 86 and 87 to be moved by the camming action of the angular extension 115. The brushes are given a forward and back motion, the pivoted links 93 and 94, and 97 and 98 allowing movement in that direction, and a sideways motion, the same links allowing a twisting movement. This complex movement of the brushes will seat in their sockets all the nuts on the carrier belt passing under the brushes and borne upon by them.

Shaft 125 carrying the sprocket 124 keyed thereto is journalled in bearings 126 and 127 mounted on frame members 23 and 26. Inside the frame member 23 at the right hand side of the machine and keyed to shaft 125 is a pulley wheel 128 which is adapted to receive a belt 129 V-shaped in cross section. The belt 129 is driven by a similar but smaller pulley 130 on the motor 131 which is disposed at the right hand side of the machine on a supporting platform 132 mounted upon a brace 133 connecting the frame members 23 and 24 at the right hand side of the machine.

It is at once apparent that any available form of power may be used to operate the machine, and that the invention is not limited to the use of an electric motor as shown. By a slight re-arrangement any prime mover could be used driving the machine through a belt.

The right hand end of shaft 125 extends beyond frame member 23 and carries keyed to it a small driving belt wheel 134 adapted to receive a belt 135 which may be of the V type. Belt 135 passes also around a second driven pulley 136, a large belt wheel upon shaft 137 which is journalled in bearings attached to the brace member 133 and not shown in the drawings. Also upon the outside of and substantially integral with shaft 137 and the driven wheel 136, is a sprocket 138 adapted to drive a chain 139 which in turn drives a large sprocket wheel 71 keyed to shaft 69.

It has been found best to make the large wheels 128 and 136 and 71 of a diameter of sixteen inches, the motor pulley 130 and belt wheel 134 of a diameter of four inches, and the small sprocket 138 of a diameter of six inches. Thus there is a series of reductions in the speed of rotation of the various wheels and shafts connected with this part of the driving mechanism. Except as here set forth the members of the pairs of driving and driven wheels are approximately equal in size so that there is no appreciable increase in or reduction of speed of rotation. Alterations in these respects would be in order if a different source of power were used or its speed changed.

The shaft 69, rotated by the wheel 71, actuates the driven sprockets 67 and 68 which co-

operate with the links of the chains 49 and cause the carrier belt to move.

Under the brushes 86 and 87 and with its upper edge bearing lightly upon the bottoms of the carrier bars 50 as they are moved past, is a strip 141 of rubber or like resilient and flexible material clamped between strips 142 and 143 which are bolted to cross piece 144. Cross piece 144 is mounted for vertical adjustment on the bottoms of screw rods 145 to which are fastened knobs 146 for easy operation. The screw rods pass through threaded apertures in brackets 147 and 148 fastened to the frame members 22 and 25, and are provided with lock nuts. Instead of passing the rods through threaded apertures they may simply be provided with two nuts, one to hold the position and the other to lock the first in place. The rubber strip 141 serves to raise the nuts slightly in the depressions in the carrier bars, thus aiding the brushes 86 and 87 in assuring proper placement of the nuts in the depressions.

The inking and printing apparatus of the machine is mounted, all but the ink supply pump, between two triangular frame members 149, which are held in proper relation to each other by shoulder tie rods 150, 151 and 152. The entire carriage thus formed is pivoted for vertical adjustment on shaft 64, one end of each frame 149 being supported by that shaft.

The other end of the carriage is supported by two screw rods 153 and 154 which are pivotally fastened to the carriage by rivets or by other suitable means passing through eyes in the rods. From the fastening the rods pass upwards through holes in frame members 22 and 25. The upper ends of the rods are threaded and extend well above frame members 22 and 25 and through a cross piece 155 which is supported above frame members 22 and 25 by rigidly fastened links 156 and 157. Above the cross member 155 two sprocket wheels 158 and 159 of equal size, appropriately drilled and threaded, are threaded onto the screw rods 153 and 154, and bearing upon the cross piece 155 support the screw rods in place. About both sprocket wheels 158 and 159 is a chain 160 which insures that if one sprocket wheel is turned to raise or lower the screw rod and the carriage, the other sprocket will turn an equal amount to raise or lower the other rod and the other side of the carriage. Thus once the carriage is properly adjusted in a level position it will always remain level while it is raised or lowered. To operate the two sprocket wheels 158 and 159, a crank handle 161 is fastened to one of them.

The printing of the marks or brands upon the nuts is done by a printing roller 162. The printing pads 163 of rubber or some other suitable material are set in depressions 165 in bars 164 which extend from end to end of the roller, the pads being fastened in the depressions by means of an adhesive, or if desired, by other means such as small screws. The number of depressions and printing pads in each bar is the same as the number of depressions in each carrier bar 50 and will be placed the same distance apart. In the form shown the carrier bars have each five depressions, so that the carrier belt carries five rows of nuts. The printing bars accordingly each have five depressions and printing pads which coincide with the apertures 54 in the carrier bars. A portion of each printing pad protrudes from the depression in which it is fastened and on the protruding end is the

stamp or design which it is desired to imprint upon the nuts.

The bars 164 are mounted on the printing roller in such a way that the lines of printing pads are separated by a distance equal to that between the apertures in adjacent carrier bars 50. Upon the printing roller 162 there are flat faces 166 as many in number as the number of bars 164 intended to fit thereon. The reverse 10 face of each bar is correspondingly flat and the flat faces of roller and bars are coextensive. The sides of the bars are substantially perpendicular to the reverse face thereof, so that when the bars are in place on the roller there is a V-shaped 15 opening between them. Into this opening is inserted a metal wedge 167 through which extends a socket headed screw 168, the head thereof being adapted to lie flush with the surface of the wedge and to be turned with a hexagonal 20 wrench inserted into the socket of the head. Threaded holes are provided in the roller 162 between the bars 164, and the screws are turned into these holes, wedging the bars 164 securely 25 in place. Should one of the bars 164 become damaged or worn or for any other reason require replacement, the wedge is loosened, the bar withdrawn and another substituted therefor while the roller is in place in the machine and without requiring a complete dismantling of the 30 roller and without requiring more than a few minutes time.

When one of the rubber printing pads becomes defective it is merely pulled out of its hole and another inserted in its place after having adhesive applied thereto. The same procedure is followed when all of the pads are changed.

The printing roller 162 is keyed to shaft 169 which is journalled in bearings 170 attached to frame members 149 at the end of the carriage 40 supported by the screw rods 153 and 154 and farthest removed from that which is pivoted on shaft 64. The right hand end of the shaft 169 protrudes through a hole in frame 149 and bears keyed thereto a sprocket 171 identical in size and 45 in line with sprocket 172 which is keyed to shaft 64, which also has keyed to it the sprockets 62 and 63 which support the carrier belt, so that the belt in moving turns shaft 64 and so drives sprocket 172 and by a chain 173, the sprocket 50 171 which in turn moves the printing roller 162. Between sprocket 171 and frame 149 is a gear wheel 174 keyed to shaft 169. A second gear wheel 175 is in mesh therewith and is keyed to shaft 176 which is journalled in bearings 177 and 55 178, mounted upon frames 149. On shaft 176 between frames 149 is a rubber roller 179. The circumference of the rubber roller 179 is in contact with the faces of the printing pad 163 as each row of them is towards such roller, and 60 the roller is of such length as to touch all the pads.

Inside the frame 149 but at the left end of the rubber roller 179, a third gear wheel 180 is keyed to the shaft 176. This meshes with a fourth gear wheel 181 which in turn is in mesh with a fifth 65 182.

Gear wheel 181 is long enough to allow end play without becoming unmeshed. It is keyed to shaft 183 which has also keyed to it a brass 70 roller 184. The teeth of gears 180, 181 and 182 are deeply cut to allow some change in the separation of the shafts.

Shaft 183 is journalled in bearings 185 and 186 at the end of an inner carriage 187. This end is 75 free except for rods 256 fastened to collars 257

and carrying springs 258 which press downward on the carriage and upward on brackets 259, bolted to frames 149, through which the rods 256 also pass, their motion downward being limited adjustably by nuts 260 on protruding ends of the rods, which are threaded for the purpose. A lock nut 261 is provided on each rod. The spring 258 urges the shaft 183 downward and the brass roll 184 into close contact with the other rollers 179 and 211 with which it cooperates.

The inner carriage 187 consists of the links 188 which support the shaft 183 adjustably fastened to links 190, by bolts 189 passing through slotted holes 192. The lower ends of links 190 bear collars 191 coinciding with holes in the links, and rod 193 passes through the collar and the links and is held rigidly by nuts 194 on the threaded ends of the rod to two brackets 195 secured to frames 149 by bolts 196. The entire inner carriage 187 is thus pivoted at its lower end.

The bearings 185 and shaft 183 as well as the gear wheel 181 are adapted to allow an endwise motion to be imparted to the brass roller 184 while it is in rotary motion. This endwise motion of the brass roller is provided by an arm 197, pivoted near its middle point by bolt 198 on a fulcrum 191 attached as by bolts 199 to the inner carriage 187. At the end of the brass roller 184 and securely fastened, as by a set screw, to the shaft at the end opposite that occupied by the gear wheel 181 is a grooved collar 200. At the end of the arm 197 is a roller 201 which fits into the groove 202 of the collar 200, being free enough to bear on one side or the other of that groove.

On the other end of arm 197 is a second roller 203 which works in the same way in an angularly disposed groove 204 in a collar 205 which is placed to rotate upon rod 193 and restrained from endwise motion by a collar with a set 40 screw, or by a shoulder on the rod or some other suitable means. Collar 205 is caused to rotate through the medium of a sprocket 206 integral therewith and a chain 207 running over sprocket 206 and over another sprocket 208 keyed to shaft 45 176. Shaft 176 in turning causes collar 205 to turn. Roller 203 follows the angularly disposed groove and causes the arm 197 to oscillate, thus moving the opposite end of the arm and through the roller 201 in the groove 202 in collar 200 imparting an endwise motion to the brass roller. The surface of the brass roller 184 is in rolling contact with the rubber roller 179, and as the two rotate the brass roller slides back and forth on its axis. The brass roller 184 and its gear 50 wheel 181 are slightly smaller than the rubber roller 179 and its gear wheel 175, so that only once in the course of many revolutions will any two particular spots on the two rollers be together.

The fifth gear wheel 182 is keyed to a shaft 209 which is journalled in bearings 210 mounted upon frames 149. In rolling contact with the brass roll 184, shaft 209 bears a felt roller 211. The felt roller and its driving gear wheel 182 55 are of slightly different diameters than the brass roller 184 and its gear wheel 181 so that the two rollers present to each other a constantly changing surface.

Above the felt roller 211 are ink drips 212 which 70 serve to keep the felt roll saturated with ink. There may be as many of these ink drips as is desired, but it is found best to have enough of them to keep the ink substantially uniform over the entire length of the felt roller. Where five 75

rows of nuts are being marked, four or five ink drips serve the purpose. They consist of a cup 213 and a spout 214. The size of the orifice of the spout determines the amount of ink that will be supplied to the rolls.

The ink drips are mounted upon a bar 215 which is fastened, as by nuts 216 on threaded ends 217 of the bar 215, to supports 218, which in turn are rigidly mounted upon rod 193 by means of 10 collars 219 and set screws 220. The position of the ink drips may be changed by turning the rod 193 or by turning the supports 218 on the rod 193 after loosening the set screws 220.

Ink is supplied to the cups 213 in any suitable 15 way, but in the present form of the device an ink pump was found to be satisfactory. The pump 221 is mounted upon a cross piece 221a attached to frame members 23 and 26 and is of the conventional type. It is operated by a reciprocating rod 222 attached to a crank plate 223 which is keyed to the end of shaft 64 and turns as the carrier belt moves. The lower end of the rod 222 passes through a collar 224 rigidly fastened thereto, a spring 225, a washer, 226, and a 25 crank pin 227, and its end is threaded to receive nuts 228 which hold the rod and a collar 229 in place.

The crank pin 227 operates a lever arm 230 which is secured to a shaft 231 protruding from 30 the pump casing. The lever arm is provided with several holes 232 into which the crank pin may be inserted for adjusting the degree of rotation of the arm. The downward movement of the arm is limited by a stop 233 against which the 35 end of the arm hits. The stop is attached to frame member 26 by a bracket 234 and a bolt 235. When the arm 230 is stopped short of its lowest position, the spring 225 allows for the further motion of the rod 222.

40 From the side of the pump 221 a pipe 236 protrudes and to the pipe are attached tubes 237 which convey the ink upwards from the pump and into the drip cups 213.

Directly above the location at which the printing pads 163 press upon the nuts in the recesses of the carrier belt is a roller 238 made of sections 239 of soft sponge rubber. The sections 239 are in the nature of rings which are slipped into place upon a base roller 240 which may be 45 of any desired material but should not be too heavy. The width of the rings or sections 239 is a little less than the distance between centers of the recesses 52 in the carrier bars 50. They are placed on the base roller 240 in such position 50 that when the entire roller 238 is centered above the carrier belt 48 each section of sponge rubber will be in position to press upon nuts in the 55 recesses 52. The roller 238 is fastened to shaft 241 which is journaled to rotate freely but with- 60 out end motion in bearings 242 at the ends of support pieces 243, which are set apart only far enough to let the roller turn freely between them without appreciable end motion. Support pieces 243 are adjustably fastened to support 65 pieces 244 by bolts 245 passing through slotted holes 246. Support pieces 244 are attached to a rod 247 by collars 248 and set screws 249, and rod 247 is held by nuts 250 without end motion but free to turn in brackets 251, which are bolted 70 to frame members 22 and 25.

The sponge rubber roller 238 is thus held in position resting of its own weight upon the carrier bars 50 and the nuts in the recesses 52 of the carrier bars, as they pass under it, the motion 75 of the carrier belt causing the roller to turn.

The soft rubber sponge of the roller allows for any inequalities in the size of the nuts carried by the belt and holds them all securely in place while the printing pads press on the under side thereof and imprint the desired mark or brand. 5

A dust shield 252 fastened to frames 149 is provided over all of the printing and inking apparatus except the printing roller 162, which must be clear to press upon the articles to be marked. A drip pan 253 is likewise provided, fastened to frames 149, under the inking and printing apparatus to prevent any ink from falling onto the under surface of the carrier belt and causing defacing marks upon the articles later placed 10 therein. 15

Upon shaft 69 and keyed thereto between the driving sprockets 67 and 68, which mesh with the chains 49 to move the carrier belt 48, is a cylinder 254 upon which are projecting pins 255, placed to intrude through the apertures 54 under the recesses 52 into the recesses from the under side of the belt 48, thus forcing out of the recesses the branded objects seated therein. This forcing out occurs as the belt moves over the sprockets 67 and 68. The branded articles thus 20 forced out of the belt fall into the sacking chute 36. The belt, freed of its load by the projecting pins, passes beneath the machine and back to the loading point. 25

The operation of the machine is clear. The 30 nuts or other articles to be marked are loaded into the hopper 35. The tail pieces 46 on the bottom of the hopper and the flexible bottom 44 and 45 are slowly vibrated by the passage beneath them of the carrier bars 50 and the depressions 52 therein. The vibration causes the nuts to be 35 dropped a few at a time onto the carrier belt 48 where they tend to settle in the recesses 52. In this they are aided by the revolving brush 74 as the belt moves under it. Having passed upward 40 under the revolving brush, the belt carries the nuts horizontally under the moving brushes 86 and 87 which seat them in their places, aided in this by the rubber strip 141 which raises them 45 slightly to allow a readjustment. As thus seated the nuts project only slightly from the openings 94 in the bottoms of the recesses, this amount of projection being fairly constant. After being 50 seated properly in the recesses the nuts are passed between the printing roller 162 which applies inked rubber printing pads 163 to their under surface, and the sponge rubber roller 238 which 55 presses on their top surfaces to hold them in place while the printing pads are applied. 55

Continuing to the end of the top path of the belt the nuts are forced from their places by pins 255 and fall into the chute 36 for sacking. 60

In the inking and printing mechanism, the ink is forced by pump 221 into drip cups 213 whence spouts 214 allow it to drip at the proper rate upon the felt roller 211, into which it soaks. The brass roller 184 pressed upon the felt roller and also upon the rubber roller 179 by springs 259 moves at the same surface speed as the felt roller but reciprocates endwise and is of different size than the other two rollers, thus distributing the ink on the felt roller, as well as upon itself, and applying it evenly upon the rubber roller which in turn applies it to the printing pads 163 as they are carried past by the printing roller 162. 65

70 It is obvious that in the construction of machines according to this invention various modifications as to material, means of fastening, source of power, mode of power transmission and arrangement of the different parts and the like 75

- will become expedient and such variations are included within the scope of this invention.
- What is claimed as new and is desired to be secured by Letters Patent of the United States is:
- 5 1. A nut marking device comprising an apertured carrier, moving brushes thereabove, printing pads therebeneath, and mechanical pressure means opposed to said pads directly opposite said pads and above said carrier.
  - 10 2. A marking device comprising a hopper having a movable bottom part, a conveyor having cup-shaped apertures in the top surface thereof and opening onto the bottom surface thereof, movable brushes above said conveyor and approximate the upper surface thereof, resisting means above said belt conveyor, a printing roller below said conveyor and under said resisting means.
  - 15 3. In a marking device, a conveyor unit comprising a bar having openings therethrough, cup shaped from the top surface of said bar and smaller at the bottom surface of said bar than at the top surface thereof, the opening at the top surface of the bar being larger than the object to be marked, and the opening at the lower surface being smaller than such object, whereby the object may be carried in the opening with its bottom surface exposed.
  - 20 4. In combination with a conveyor having depressions therein, and rotative power supply means, means for seating articles in said depressions comprising flat brushes mounted on a movable frame, and means for moving said frame and brushes comprising a rotating shaft, an angularly offset shaft on one end thereof, a rider on said angularly offset shaft, and pivoted coupling means between said rider and said movable frame.
  - 25 5. In a branding device having a vertically movable printing frame, vertical adjusting and holding means for said frame comprising non-rotating threaded rods upon said frame, threaded sprocket wheels on said threaded rods, support means for said sprocket wheels, a chain about said sprocket wheels, and means for manually turning said sprocket wheels.
  - 30 6. A printing roller comprising a core member having flat faces about its periphery and threaded holes between said faces, a plurality of recessed bars adapted to lie on the flat faces of said core member, rubber printing pads removably secured in the recesses in said bars, wedge blocks tapered toward the center of said core, adapted to fit between said bars on said core member to hold the bars on the core member and having holes therein aligned with the holes between the faces on said core member, and headed studs extending through the holes in said wedge blocks and threaded into the threaded holes in said core member, whereby to secure said wedge blocks to the core and hold said bars in place on said core.
  - 35 7. In combination with a conveyor having article holding means therein, means for receiving articles to be carried by said conveyor, a lip on said means and movable adjacent said conveyor, and means for moving said lip, said lip moving means keeping said lip adjacent a holding means in said conveyor over a selected portion of the travel of the conveyor, and then moving said lip to adjacent a succeeding holding means in said conveyor, whereby to load articles into said holding means.
  - 40 8. A printing roller comprising a core member having flat faces about its periphery and threaded holes between said faces, a plurality of printing bars adapted to lie on the flat faces of said core member, wedge blocks tapered toward the center of said core member adapted to fit between said bars on said core member and having holes therein aligned with the holes between the faces on said core member, and headed studs extending through the holes in said wedge blocks and threaded into the threaded holes in said core member, whereby to secure said wedge blocks between said bars and hold said bars in place on said core.
  - 45 9. The method of marking nuts which comprises the steps of arranging the nuts in selected angular positions in a selected path by agitating them from above, moving them along such path while sustaining them in such selected angular positions, and marking the bottom portions of such nuts from beneath.
  - 50 10. The method of arranging small objects in selected angular positions for printing, which comprises moving the objects along a selected path, and agitating the objects by moving contacts with the upper portions thereof in a plurality of directions in a plane parallel to the selected path.
  - 55 11. A nut marking device comprising an apertured carrier, means above the carrier for seating nuts in the apertures thereof by moving contacts therewith, printing means beneath the carrier, and mechanical pressure means above the carrier and opposite said printing means.
  - 60 12. A nut marking device comprising an apertured carrier, means above the carrier adapted to move over the carrier to seat nuts in the apertures thereof, printing means beneath the carrier, and means above the carrier and opposite the printing means for applying mechanical pressure to nuts in the apertures.
  - 65 13. A nut marking device comprising an apertured carrier, means above the carrier adapted to move over the carrier in contact with nuts on the carrier to seat the nuts in the apertures thereof, resilient printing means beneath the carrier and adapted to contact nuts in the apertures from beneath, and resilient means above the carrier and opposite the printing means for resiliently applying mechanical pressure to nuts in the apertures.
  - 70 14. A nut marking device comprising an apertured carrier, brushes adapted to move in a plurality of directions in a plane above the carrier as the carrier moves to orientate and seat nuts in the apertures in the carrier, resilient printing means, and resilient nut holding means, said printing means and said holding means being so positioned that the carrier passes between them as it moves and being operable upon the nuts after they are orientated and seated in the apertures in the carrier to print upon the nuts from one side and to hold the nuts from the other side while they are being printed.
  - 75 15. The method of marking nuts which comprises the steps of arranging the nuts in selected angular positions in a selected path by agitating them from above, moving them along such path while sustaining them in such selected angular positions, holding the nuts from above against disarrangement, and marking the bottom portions of such nuts from beneath.

JOHN E. TRUNK.
